UNITED STATES PATENT OFFICE.

RALPH F. FOX, OF HARRISBURG, PENNSYLVANIA.

DIRIGIBLE AIRSHIP.

Application filed August 30, 1926. Serial No. 132,650.

The object of this invention is to provide special means for mounting the engines and propellers of an airship of the general type disclosed in my pending application for Patent Serial No. 92,827, filed March 6, 1926.

A further object is to provide a plurality of transversely extending girders to be mounted on the longitudinal girders of the lower portion of the craft, these transverse 10 girders projecting laterally from the hull and being adapted to mount an engine on opposite end portions thereof, for driving propellers mounted as specified below.

A further object is to provide driving 15 means for this type of air craft, comprising a series of forward propellers on each side of the vessel, these propellers having their axes of rotation in alinement, or a portion of them being so positioned, and a series of propellers mounted on the laterally projecting 20 ends of the transverse girders, near the stern of the vessel, and on each side thereof.

A further object is to provide a housing 25 for each of the engines, the housings being constructed as indicated below.

With the foregoing and other objects in view, the invention consists in the novel construction and arrangement of elements described, illustrated and claimed; it being understood that modifications may be made 30 within the scope of the claims without departing from the spirit of the invention.

In the drawings forming part of this application,

Figure 1 is a view of the machine in side elevation.

Figure 2 is a horizontal section, longitudinally of the structure, and on line 2—2 of Figure 1.

Figure 3 is a vertical transverse section thru the lower portion of the structure.

Figure 4 is a plan view showing one of the transverse girders, and showing extension members on opposite ends of the girder, 45 upon which a plate for mounting the engine or engines, is to be secured.

Figure 5 is a view vertically and transversely of one of the girders, such as that shown in Figures 3 and 4, with the hood or 50 housing for one of the engines in elevation, the propeller also being illustrated.

Figure 6 is a top plan view of the structure of Figure 5.

Figure 7 is a vertical section on line 7—7 55 of Figure 5.

Figure 8 is a vertical section on line 8—8

of Figure 7, the engine in both Figures 7 and 8 being in elevation.

Figure 9 is a detail in section, showing the mounting of one of the rudders in a 60 bracket carried by an end frame-inclosing element.

The main portion of the machine includes a plurality of sections, designated 10, and comprising individual frames of circular 65 form, the gas cells being mounted between the elements of the frames. These cells are not illustrated in this case, but are fully shown in the application above referred to, and they are to be mounted in a metallic 70 sheathing within the rigid structure.

The main structure of the machine includes the nose portion 11, and the stern structure 12, the rudders and controls therefor being illustrated somewhat conventionally in Figure 1 of the present case, and the mounting of the vertical rudder being shown in detail in Figure 9. Pontoons 13 and 14 form a part of the lower or gondola construction, and the series of windows is 80 shown at 15, in Figure 1.

In Figure 3 a portion of one of the circular frames, or sections 10, is illustrated, and vertically extending braces or posts, designated 18, are mounted between the longitudinal girders 19 and said elements 10 of Figure 3, and are secured in any suitable manner.

In Figure 2 I have illustrated a number of transverse girders of the built-up type, 90 these girders being designated 20, and being shown partly in side elevation and top plan respectively, in Figures 3 and 4. These girders 20 are proportioned to extend laterally beyond the sides or walls 21, and are of sufficiently substantial construction to permit 95 of the mounting of an engine on each end of the individual girders 20.

The engines are shown conventionally and are designated 24, and it will be observed that five engines or motors are mounted on each side of the forward portion of the craft, and similar provision is made at the rear, the series of motors last named being mounted however forwardly of the stern structure 12, as the construction is disclosed in the present case. It is obvious that the exact position of the engines or motors is not material, so far as the character of the mounting is concerned, but a laterally projecting girder or truss is provided for each 105 pair of motors, one unit of each pair being 110

on each side of the air craft. The propellers 25 are mounted respectively on the shafts of the motors 24, and as illustrated in this case, the axes of rotation for each group of propellers on a given side of the machine, and forwardly from the middle portion thereof, may be in alinement,—the same arrangement being followed with reference to the motors and propellers for the rear portion of the machine.

Figure 4 shows that each transverse girder or truss 20 includes or has mounted thereon in any suitable manner a plurality of extensions, such as 26, the upper portions of the extensions being in the same plane as the upper portion of the girder on which they are mounted. A heavy plate 28 is secured to the end portions of each girder 20, and to the extensions 26 carried thereby, to form a platform or the like on which the motor or motors may be mounted.

Each motor 24 includes a main shaft 24', and the motors are supported by means of leg braces 30 of the form illustrated in Figure 7, these elements 30 being bolted to angle bars 31 mounted on plate 28. The angle bars 31 have their vertical flanges extending upwardly and their horizontal flanges extending inwardly, so that a firm support for the elements 30 and the motors per se is provided.

A passage way 35 is provided on that portion of each truss or girder 20 between the side of the vessel and the housing for the engines or motors. This passage way is protected by a railing or railings 36, and access is obtained to the motors 24 thru openings adapted to be closed by doors 38.

The housings or hoods for the motors each include a plurality of cover members such as 40 and 41 hinged or pivoted at 42 and carrying handles such as 43. A door 44 provides access from passage way 35 to the housing of the motor, and openings in the walls of the housing are partly covered by shield members 45 of a well known type, employed in this class of apparatus.

It will be observed from Figure 5 that the transverse girders or trusses 20 are built up of angle bars such as 21', braced as required, and that the lateral extensions from these girders 20 are built on to the sides, being bolted thereto, in order to provide a structure forming a flat base for mounting the engine.

Figure 9 shows a rudder 47 pivotally mounted by bolt or rod 48 in bracket 49 of element 12 inclosing or enveloping the rear girder construction.

Having described the invention what is claimed is:—

1. In a device of the class described, a main hull structure and a keel and gondola structure connected therewith, a series of spaced girders extending transversely of the structure last named and having their ends projecting laterally therefrom, motors mounted on said projecting ends of the girders, lateral extensions carried by the ends of each of the girders, motor supporting means carried by the ends of the girders and by the lateral extensions, and propellers driven by the motors.

2. In a device of the class described, a main hull, a keel and gondola structure connected with the hull and including longitudinal girders, transverse girders extending across the longitudinal girders and supported thereby, motors carried by the ends of the transverse girders, and propellers driven by the motors and mounted outwardly from the sides of the keel and gondola structure, housings for the individual motors, and means affording access to the interior of the housings, across the ends of the girders and from the keel and gondola structure.

3. In a device of the class described, a main hull structure, a keel and gondola structure including longitudinal girders and vertical supporting devices connected with the main structure, a series of spaced girders extending thru the keel and gondola structure and carried transversely of the longitudinal girders, the transverse girders projecting laterally beyond the sides of the keel and gondola structure, extensions carried by the projecting ends of the girders, plate members extending across said projecting ends and across the extensions, motors carried by the plate members, means for retaining the motors, said motors being positioned to have their shafts in alinement on each side of the main structure, propellers carried by the shafts, and housings for said motors, these housings each including a plurality of hingedly mounted elements for closing openings providing access to the housings and to the motors therein.

In testimony whereof I affix my signature.
RALPH P. FOX.
